UNITED STATES PATENT OFFICE

CLARENCE A. WILLSON, OF MADISON, WISCONSIN, ASSIGNOR, BY MESNE ASSIGNMENTS,
TO AMERICAN FACE BRICK RESEARCH CORPORATION, A CORPORATION OF ILLINOIS

FACING FOR WALL BUILDING BLOCKS

Application filed November 12, 1928. Serial No. 318,627.

This invention is directed to an improved facing for a wall building unit, such, for instance, as a concrete block of rectangular form and of the size and character commonly 5 in use at the present time.

The invention is specifically directed to the configuring of the exposed face of such a block in such a way as to simulate brickwork laid in courses and presenting a novel and interesting pattern. The exposed surface of the block is divided in such a way as to display multiples of the corresponding dimensions of ordinary bricks, the pattern being of such a nature that when the blocks are laid 10 into a wall it will be difficult, or impossible, to discern the joints or divisions between the individual blocks, but, on the contrary, such lines will blend into and harmonize with the division lines between the surface sections of 15 the individual blocks in such a way as to closely simulate the appearance of brickwork.

It is generally recognized that the small units of brickwork present a more attractive appearance than the larger concrete blocks, 20 but it is cheaper to manufacture and build with the larger units. In the past, attempts have been made to provide building blocks with a surface pattern resembling brickwork, but the bonding or overlapping that is characteristic of brickwork has made it impossible 25 to produce blocks of rectangular configuration. Such blocks have commonly been stepped or notched at their ends to conform to the normal brick pattern, or have presented 30 the appearance of cut bricks at the ends of the blocks, in violation of what is recognized as conformable to the highest standards of brick laying.

In the present invention, the desirable rectangular outline of the building block has 35 been retained by providing a surface pattern which, when the wall is constructed, presents the appearance of brick courses in which stretcher bricks alternate with header bricks in such a way as to present a novel and interesting and highly ornamental framework bond or pattern. At the same time, the arrangement is one which effectively conceals 45 the location of the joints between the blocks and everywhere presents the appearance of

bricks laid in courses, the actual joints being indistinguishable from the simulated joints formed in the surface of the blocks.

Further objects and details of the invention will appear from the description of the same, 55 in conjunction with the accompanying drawings, wherein,

Figure 1 is a front elevation of a wall built of building blocks embodying the features of 60 the present invention;

Figs. 2 and 3 are front elevations of individual blocks showing alternate arrangements of the brick designs;

Fig. 4 is a perspective view of a concrete block having the brick design of Fig. 3 cast 65 in its face;

Figs. 5 and 6 are perspective views of fractional blocks, similar to the block of Fig. 4, worked out in normal brick units to be used as needed at the ends of the courses or at 70 window or door openings, or elsewhere; and

Fig. 7 is a block having the brick units made up of thin clay brick tile cemented to 75 the face of the concrete block.

As shown, the blocks are of generally rectangular dimensions, although they are recessed or cored in any suitable manner to reduce weight or provide dead air spaces of the character commonly used in concrete building blocks or the like. It will be understood, 80 therefore, that where a block is referred to as rectangular it has reference to its general extreme dimensions, irrespective of the presence or absence of holes, recesses or similar indentations.

The exterior or facing surface, however, is of truly rectangular configuration, and, as shown, is slightly in excess of the length of a brick and a half, and in width slightly in excess of the thickness of two bricks. The face surface is divided by a longitudinal groove 10 into upper and lower course sections, and each course section is divided by a vertical groove 11 into a full brick section 12 and a half brick section 13, the respective full brick and half brick sections in the adjoining courses being in stepped or staggered arrangement. Each block thus presents a face surface in simulation of the portions of 90 two brick courses, each course presenting the 95

appearance of a stretcher brick and a header brick in adjoining relation.

The grooves 10 and 11 are of a width and depth to simulate the appearance of brick joints, and these grooves may be rectangular, V-shaped, semi-circular, or having a bead-like projection, or may be of different colored material, or patterned in any other way which simulates mortar joints of the character or color commonly employed in ordinary brickwork. In fact, the division lines (grooves in the present instance) may be afforded by any device that isolates or sets off in appearance the bricklike sections of the block, so that it will present the appearance of actual bricks divided from one another by joints of the character commonly employed.

The block may be completely formed of cement or concrete or other plastic material, as in Fig. 4; or as in Fig. 7, it may consist of a concrete backing having a brick or tile facing 14 cemented to the surface of the concrete to afford an actual brick finish in lieu of the imitation brick finish afforded by the completely molded block of Fig. 4. The division lines, grooves or seams of the brick or tile surface shown in Fig. 7, are of the same character as those heretofore described, and need not be particularly referred to. Furthermore, it will be understood that the block of the present invention may be made of any suitable material, with or without a special surface layer, and that the invention is concerned rather with the method of dividing the surface into sections having the specially defined characteristics than to the composition of material or materials of which the block is composed; and it will be further understood that, if desired, full standard bricks may be imbedded and unified into a block possessing the surface pattern or bond of the present invention, and that such a built up block is intended to be covered and included by the claim, unless otherwise indicated.

Referring now to the manner of combining such blocks into a wall, it will be noted by reference to Fig. 1 that the division lines between the individual blocks are conveniently indicated by dotted lines in the upper portion of the wall, although it will be understood that in the actual wall, when properly constructed, the seams or division lines will be indistinguishable from the grooves which simulate them, so that the wall as a whole will present the brickwork pattern indicated in the figure.

It will further be observed that the blocks in a given course overlap by one-third the blocks in the vertically adjacent courses, although the overlap in each instance will be one-half the length of the adjacent section 12 representing the full length of a stretcher brick in the adjacent course. This arrangement provides an adequate overlap between

the blocks to fully conform to structural requirements, while at the same time presenting the appearance of a half overlap between vertically adjacent brick sections 12-12.

This method of overlapping will bring the vertical division lines or grooves 11 in adjacent blocks into registering relation with one another, which gives the appearance of a continuous vertical joint run through two brick courses, and harmonizing in pattern arrangement with the actual vertical joints which span the width of two brick courses. This arrangement brings the header brick sections 13-13 into continuous diagonal alignment, in one oblique direction, and into interrupted diagonal alignment in the other oblique direction, which, however, presents an attractive pattern effect in the completed wall, which thus presents the appearance of a brick wall intentionally patterned to produce an attractive or ornamental appearance.

The wall shown in Fig. 1 is composed of blocks presenting the brick pattern arrangement of Fig. 2, but a similar effect, in reverse arrangement, however, would be secured by building the wall entirely of bricks presenting the pattern shown in Fig. 3, in which latter case the diagonal aligning of the header bricks would be reversed as compared with that presented in Fig. 1.

Figs. 5 and 6, as before stated, show fractional blocks which may be used as occasion requires. The fractional brick of Fig. 5 shows two header sections 15 with an intervening groove or division line 16, while the fractional brick shown in Fig. 6 shows two header brick sections 17 in adjacent relation in the same course, together with a full stretcher brick section 18 in the adjoining course.

In the wall shown in Fig. 1, the fractional brick of Fig. 5 is located at the point 19, while a fractional brick of the character shown in Fig. 6 is located at the point 20. These fractional bricks carry out and extend the wall design, and when properly fitted in place are indistinguishable from the full sized constituents of the wall structure.

The invention is one which conserves the desirable characteristics of the concrete block construction, and at the same time disguises the character of the block in such a way as to greatly enhance the appearance of the completed wall by the presentation of an attractive brick pattern, and by relieving the monotony in appearance which is the invariable characteristic of ordinary concrete block construction.

I claim:

A wall composed of blocks, each block having an exposed face in simulation of constituent portions of two brick courses, each course consisting of a full length stretcher brick section and an adjacent header brick section, the stretcher brick sections and the header

brick sections in the two courses being in reverse relation and the sections being separated by grooves simulating the mortar joints in brickwork, the blocks being laid in the wall

5 in two-thirds overlapping relation to bring the simulated joints between the stretcher and header sections in one block into vertical register with similar simulated joints in the vertically adjacent block, with the contiguous

10 header sections and the contiguous stretcher sections adjacent the simulated joints standing in diagonal relation to one another and each block terminating in position to bring the actual vertical joints into register with

15 the middle of the contiguous simulated stretcher brick sections in the vertically adjacent blocks, and the completed wall presenting the appearance of brick courses, each course consisting of alternate stretcher and

20 header bricks with the header bricks in adjacent courses in continuous diagonal alignment in one direction and in interrupted diagonal alignment in the other direction.

In witness that I claim the foregoing I
25 have hereunto subscribed my name this 5th
day of November, 1928.

CLARENCE A. WILLSON.
